UNITED STATES PATENT OFFICE.

GURDON CONKLING, OF CONKLINGSVILLE, NEW YORK, ASSIGNOR TO CAROLINE A. CONKLING, OF SAME PLACE.

IMPROVED DEVICE FOR TAPPING BOOTS AND SHOES.

Specification forming part of Letters Patent No. 43,814, dated August 9, 1864.

To all whom it may concern:

Be it known that I, GURDON CONKLING, of Conklingsville, in the county of Saratoga and State of New York, have invented a new and Improved Device for Tapping Boots and Shoes; and I do hereby declare that the following is a full, clear, and exact description of the same, reference being had to the accompanying drawings, making a part of this specification, in which—

Figure 1 represents a longitudinal vertical section of my invention. Fig. 2 is a detached plan or top view of the sole-plate. Fig. 3 is a plan or top view of the invention.

Similar letters of reference in the three views indicate corresponding parts.

This invention consists in the employment or use of a sole-plate, made of metal or other suitable material, and provided with a projecting toe-flange, in combination with a piece of board cut out according to the outlines of a last, and with a wedge, in such a manner that by means of said last-shaped board and wedge the sole-plate can firmly be secured on the inside of a boot or shoe, and a new half-sole can be put on without the necessity of having a full last corresponding to the boot or shoe to be soled, and so that any person, particularly soldiers in the field, will be enabled to provide themselves with the necessary means for the purpose of tapping their own boots or shoes.

To enable those skilled in the art to make and use my invention, I will proceed to describe it.

A represents the sole-plate, which may be made of metal or any other suitable material. For the sake of cheapness and of convenience in using it I prefer to make this plate of cast-iron. It must be made to correspond to the size of the boot or shoe to be tapped, but one plate can be used for right and left and also at least for three different sizes—viz., the size for which it is made and one size larger and

one smaller. It is provided with a V-shaped toe-flange, a, which serves as a bearing for the points of the piece of board B and of the wedge C. The piece of board is cut out of an ordinary plank of the thickness of one inch (more or less) or of any other convenient piece of wood somewhat in the shape of a last, with a flat inclined surface, b, which forms the bearing for the wedge C.

The operation is as follows: The sole plate A is placed into the boot or shoe to be soled, and by means of the last-shaped piece B and wedge C it is pressed down firmly, so that it affords a firm support, and the half-sole can be attached to the boot or shoe by means of nails or pegs in the usual manner.

If the half-sole is to be attached with nails, the sole-plate ought to be made of cast iron or other suitable metal, so that the nails on being driven in will clinch themselves.

If wooden pegs are to be used, the sole-plate may be made of hard wood or any other suitable material. I prefer to use cast-iron, however, not only for the sake of causing the nails to clinch themselves, but also because said plates can be made in the easiest and cheapest manner when they are cast. The wedge C and the last-shaped piece B can be cut out of any piece of wood, and a person being provided with the sole-plate, nails, and hammer will thus be able to tap his own boots or shoes in the most convenient manner.

What I claim as new, and desire to secure by Letters Patent, is—

The employment or use of the sole plate A, in combination with a last-shaped piece, B, and wedge C, all constructed and applied in the manner and for the purpose substantially as specified.

GURDON CONKLING.
